COMBINED DISPLAY AND CONTROL CONSOLE FOR AN INFORMATION FILING AND RETRIEVAL SYSTEM

Charles F. Grossman, Sunnyvale, Calif., and Marvin A. Southcott, Baltimore, Md., assignors to Ampex Corporation, Redwood City, Calif., a corporation of California

Filed Oct. 23, 1965, Ser. No. 87,826

Term of patent 14 years

(Cl. D26—5)

FIGURE 1 is a perspective view taken from the front, top, and left side of a combined display and control console for an information filing and retrieval system showing our new design; and

FIGURE 2 is a perspective view taken from the rear, top and right side thereof.

We claim:

The ornamental design for a combined display and control console for an information filing and retrieval system, substantially as shown and described.
